[57] **CLAIM**

The ornamental design for a shoulder sun shield, as shown and described.

DESCRIPTION

FIG. 1 is a front, perspective view of a shoulder sun shield, showing my new design as worn on an individual as indicated by phantom lines which do not form part of the claimed invention;

FIG. 2 is a left side-elevational view thereof;

FIG. 3 is a right side-elevational view thereof;

FIG. 4 is a top plan view thereof;

FIG. 5 is a bottom plan view thereof;

FIG. 6 is a front-elevational view thereof; and,

FIG. 7 is a rear-elevational view thereof.
